UNITED STATES PATENT OFFICE

GEORGE C. EVANS, OF PERTH AMBOY, NEW JERSEY

CONCRETE TANK CONSTRUCTION

Application filed March 8, 1929. Serial No. 345,544.

This invention relates to improvements in concrete tank construction and more particularly to concrete tanks suitable for the support and insulation of lead electrolytic cells.

5 The invention has for its object the provision of a concrete tank construction composed of a plurality of interchangeable units which may be molded or cast separately and then assembled together at any desired location.

10 A further object of the invention is to provide a support for lead electrolytic cells which will be more durable and resilient than the wooden supports in general use at present and at the same time more easily assembled and 15 paired than monolithic concrete construction.

Other objects of the invention will appear from the detailed description below.

The invention broadly comprises a tank, vat or container constructed of a small number 20 of reinforced concrete units, namely: bottom units, end units and side units, molded into shapes suitable to be assembled into an individual tank; or, by using a sidewall of a tank as a partition common to two tanks, into 25 a series of tanks or a tank comprising a plurality of compartments.

The invention will be more particularly described with reference, for the purpose of illustration, to the accompanying drawings, 30 in which:

Fig. 1 is a perspective view in partial section of an embodiment of the invention in which a series of tanks, or as it may be equally well expressed, a tank subdivided into a plurality of compartments, is provided as a support for a series of lead electrolytic cells;

Fig. 2 is a partial plan of the embodiment of Fig. 1;

Fig. 3 is an end elevation in partial section; 40 Fig. 4 is an end elevation; and

Fig. 5 is a section on the line 5—5 of Fig. 3. The main units of the tank construction are the base 1, the side units 2, the partition units 3, and the ends units 4 and 5.

45 The base unit 1 comprises a rectangular reinforced concrete slab, provided with slots 6 adapted to receive the lower edges of side units 2 and partition units 3; it is also provided with a plurality of leak holes 7 so spaced as to avoid exposing any metal rein-

forcement, and carries openings 8 for draining the contents of the cells. The leak holes 7 ensure the prompt detection of any leaks in the lead cell.

The side units 2 consist of rectangular reinforced concrete slabs adapted to fit into the slots 6 of the base member and provided at each end with a plurality of projecting threaded rods 9. These rods are securely embedded in the concrete and may advantageously extend lengthwise through the side units and project at each end thereof, thus serving both to reinforce the side members and to securely hold the construction together. The rods are adapted to pass through corresponding holes suitably cored in the end units to be described.

55 The partition units 3 consist of rectangular reinforced concrete slabs substantially identical with the side units 2 described above, differing principally in that the side units are advantageously provided on their outer sides with reinforcing elements 10.

The end units consist of substantially rectangular reinforced concrete slabs 4 and 5; 60 units 4 being adapted for use in constructing the inner compartments of a series and units 5 being adapted for use in constructing the end compartments of a series.

65 The end units 4 are provided at each side with lateral extensions 11 adapted to fit into notches formed by corresponding lateral extensions on the adjacent end units and provided with holes adapted to receive the projecting threaded rods 9 of the side and partition units. The end units may be provided with holes 12 and notches 13 for the introduction and discharge of electrolyte. End units 5 are provided with the lateral extensions 11 only on one side.

70 In assembling the construction the side units 2 and partition units 3 are positioned in the corresponding slots 6 of base unit 1, and the end units 4 and 5 are slipped over the projecting threaded rods 9 so that the partition units 3 are supported at each end by the interlocking projections 11 of two adjacent end units.

75 The joint thus formed is covered with an 100

iron plate 14 provided with holes spaced to correspond to and receive the rods 9. The plates 14 are then drawn up tight to the interlocking projections by means of nuts on the threaded ends of the rods 9. The plates 14 thus support that part of the end units not directly supported by the rods.

All joints and seams may thereafter be filled with grouting and the construction is ready to receive the lead lining 15 which forms the electrolytic cell proper. Electrodes may be positioned as shown at 16 and 17 in Fig. 3.

The whole construction is advantageously supported on concrete posts 18.

The advantages of the above described support for lead electrolytic cells include the following:

The various units of the construction may be molded and stored away to season or age.

One set of metal molds may be used to cast any number of units.

Since the units of one kind would all be cast from the same mold, they would be uniform and interchangeable.

The construction is easily assembled due to the small number of parts to be handled.

Any number of compartments or cells may be constructed in a series.

Any individual cell or part of a cell may be renewed.

The replacement of a damaged unit from a stock supply would require less time than the repair of a wooden frame.

The construction is permanent and is absolutely free from shrinkage or change in dimensions during its life.

The construction is rigid without the use of any sway bracing other than that provided by the interlocking notches and large bearing surface of the end units.

The lead electrolytic cell is more easily placed and beat into place than is the case with wood as there is no resilience in concrete.

The lead cell requires but one dressing whereas the wood frame construction requires two operations due to the shrinkage of wood.

It will be understood that the invention is not limited to the particular details described above for the purpose of illustration, but that the invention broadly comprises a concrete tank construction consisting of a rectangular base member provided with slots in its upper surface adapted to receive the lower edges of a plurality of side members, including in the scope of the term "side members" also partition members, a plurality of rectangular side members provided with a plurality of rods extending longitudinally therethrough and having a threaded portion projecting from each end thereof, and a plurality of substantially rectangular end members provided on at least one lateral edge with rectangular lateral extensions adapted to

fit into notches formed by corresponding lateral extensions on adjacent end members, said lateral extension being provided with holes spaced to correspond to and adapted to receive the projecting threaded rods of the side members.

In the following claims the terms "side members" is to be understood as including also partition members.

I claim:

1. A reinforced concrete tank construction comprising a base member, a plurality of side members and a plurality of end members, said base member having its upper surface provided with a plurality of longitudinal slots adapted to receive the lower edges of said side members, said side members being provided with a plurality of threaded rods projecting from each end thereof, and said end members being provided on at least one lateral edge with rectangular lateral extensions adapted to fit into notches formed by corresponding lateral extensions on adjacent end members, said lateral extensions being provided with holes spaced to correspond to and adapted to receive the projecting threaded rods of the side members.

2. A reinforced concrete tank construction comprising a base member, a plurality of side members and a plurality of end members, said base member having its upper surface provided with a plurality of longitudinal slots adapted to receive the lower edges of said side members, said side members being provided with a plurality of rods extending longitudinally therethrough and having a threaded portion extending from each end thereof, and said end members being provided on at least one lateral edge with rectangular lateral extensions adapted to fit into

notches formed by corresponding lateral extensions on adjacent end members, said lateral extensions being provided with holes spaced to correspond to and adapted to receive the projecting threaded rods of the side members.

3. A reinforced concrete tank construction comprising a base member, a plurality of side members, a plurality of end members and a plurality of iron bracing members, said base member having its upper surface provided with a plurality of longitudinal slots adapted to receive the lower edges of said side members, said side members being provided with a plurality of rods extending longitudinally therethrough and having a threaded portion extending from each end thereof, said end members being provided on at least one lateral edge with rectangular lateral extensions adapted to fit into notches formed by corresponding lateral extensions on adjacent end members, said lateral extensions being provided with holes spaced to correspond to and adapted to receive the projecting threaded rods of the side members.

4. A reinforced concrete tank construction comprising a base member, a plurality of side members, a plurality of end members and a plurality of iron bracing members, said base member having its upper surface provided with a plurality of longitudinal slots adapted to receive the lower edges of said side members, said side members being provided with a plurality of rods extending longitudinally therethrough and having a threaded portion extending from each end thereof, said end members being provided on at least one lateral edge with rectangular lateral extensions adapted to fit into notches formed by corresponding lateral extensions on adjacent end members, said lateral extensions being provided with holes spaced to correspond to and adapted to receive the projecting threaded rods of the side members.

threaded rods of said side members, and said bracing members being rectangular iron plates provided with holes spaced to receive the ends of said projecting rods and adapted to support the interlocking lateral extensions of a pair of said end members.

In testimony whereof, I affix my signature.
GEORGE C. EVANS.
